UNITED STATES PATENT OFFICE.

HENRY H. HARRINGTON, OF GALION, OHIO.

FASTENING DEVICE FOR CLOSURES.

1,357,864.

Specification of Letters Patent.

Patented Nov. 2, 1920.

Application filed November 24, 1919. Serial No. 340,192.

To all whom it may concern:

Be it known that I, HENRY H. HARRINGTON, a citizen of the United States, residing at Galion, in the county of Crawford and

5 State of Ohio, have invented certain new and useful Improvements in Fastening Devices for Closures; and I do declare the following to be a full, clear, and exact description of the invention, such as will enable others skilled in the art to which it ap-

10 pertains to make and use the same.

This invention relates to improvements in devices for fastening closures over openings in casings, and it has more particular reference to devices for fastening closures in position on burial vaults.

15 The principal object of the invention is to provide fastening devices for the above mentioned purpose which are constructed of ordinary bolts, nuts, and castings, thereby reducing the cost of manufacture of such fastening devices.

20 Another object of the invention is to provide novel fastening devices of the above mentioned character which have means incorporated therewith which enable the operator to accurately determine whether or not the locking members are in effective or released position, even though such locking members are not visible to the operator. Other objects and advantages of the invention may become apparent during the course 25 of the following description.

25 In the accompanying drawing forming a part of the specification and in which like numerals are employed to designate like parts throughout the same,—

30 Figure 1 is an end view of a burial vault embodying the improvements of my invention.

35 Fig. 2 is a vertical section through the burial vault, looking from the closed end, illustrating my locking devices in applied and released positions.

40 Fig. 3 is a vertical section on the plane of the line 3—3 of Fig. 2, illustrating one of the locking members in applied position.

45 Fig. 4 is a transverse section on the plane of the line 4—4 of Fig. 2, showing the locking member in released position.

50 Fig. 5 is an enlarged detail perspective view of one of the locking members constructed in accordance with my invention.

55 Fig. 6 is a view like Fig. 5 showing another side of the locking member.

In the drawings, wherein for the purpose

of illustration is shown preferred embodiment of my invention the numeral 1 designates the body portion of a grave vault which is provided at one of its ends with an 60 opening which is surrounded by an inwardly extending continuous flange 2. It is well known that this type of burial vault serves to permit the casket to be inserted through the opening at its end. After the 65 casket has been introduced into the vault, the vault is closed by the usual closure, which in this instance is in the form of a closing plate 3 which abuts the flange 2, and when it is locked in position it forms a 70 substantially air tight and water proof vault. While the description, so far as it has gone, refers to a burial vault, I desire it to be understood that my locking members are also equally well adapted to be used in 75 connection with any type of a casing having an opening therein which is closed by means of closure or closing plate. However, in order to enable the reader to acquire a thorough understanding of the device, the 80 following description will associate my locking members with a burial vault. These locking devices as will be hereinafter specifically described are to be positioned about the marginal portion of the closing plate 3 85 so as to permit them to co-act with the flange 2 and retain the plate 3 in position.

As shown, the closing plate 3 is provided on its inner face with a plurality of locking members 4 which are rotatably mounted 90 thereon. Each locking member is preferably made from a single casting and includes a nose 5 which is adapted to engage the flange 2. In order to enable this nose 5 to readily ride over the edge of the flange 2 95 and come into effective engagement it will be seen that the outer face thereof is tapered as shown at 6. By tapering the face of the nose 5 in the manner shown it will be seen that the device will not only be permitted to 100 readily move to applied position, but it will also effect a cam action, and tend to pull the plate 3 tightly against the flange 2, or against the flexible packing member 2^a, which is sometimes placed between the plate 105 3 and the flange 2. Locking member 4 is provided with a flange 7 which is disposed transversely to the nose 5, and the outer edge thereof is curved in a line approximately concentric with the axis of rotation, and this 110 flange carries a pair of spaced laterally extending lugs 8 and 9, the purpose of which will

hereinafter be set forth. The numeral 10 designates a hub which has a socket 11 formed in its inner face, the walls of which are non-circular as shown, to permit a nut 12 to be 5 non-rotatably seated therein. Opening from this socket 11 and extending through the outer face of the locking member, is a hole or opening 13, the purpose of which will be described as the description proceeds.

10 In order that each of the locking members may be rotatably mounted to accomplish the desired results, I employ a plurality of bolts 14, each of which extends through an opening in the plate 3, through the hole 13, and 15 is threadedly engaged with the nut 12, being provided on its free end with a stop 15. This stop 15 may be of any suitable construction, but I have shown it as being in the form of a nut which is bent by means of 20 a hammer or the like, to cause its threads to bite into the threads on the bolt 14 and thereby become locked in position on the bolt. However, as before stated, the exact construction of this stop is not essential and 25 any suitable means may be employed for the purpose.

Cast integral with, or otherwise properly secured to the plate 3, are a plurality of combined stop and guide members 16, which 30 as shown, are disposed in close proximity to the locking members 4. Each of these members 16 is in the form of a catch and a portion thereof extends over the flange 7 and serves as a guide. Inasmuch as each of 35 these members 16 is positioned between the spaced lugs 8 and 9 on the flange it will be seen that when the locking members are rotated either to effective or ineffective position, one of the lugs will engage the member 40 16 and limit the turning movement of the locking members 4. As the members 16 are made of metal and as the lugs 8 and 9 are also of metal it will be seen that when one of the lugs comes into engagement with the 45 members 16, a clicking noise will be transmitted to the operator, and in this manner he may accurately determine whether or not the locking members are in effective or ineffective position.

50 In order to move the locking members to locking position it is obvious that this may be done by applying a wrench to the head of the bolt 14. To describe this more thoroughly we will assume, for example, that a locking member is in the position shown in Fig. 4, in which position it is released. In this position it will be noted that the stop 15 and the nut 12 are in tight contact with each other and the lug 8 is in engagement 55 with the member 16. By turning the head of the bolt 14 from the left to the right it will be seen that the locking member 4 and the part associated therewith will be rotated until the lug 9 engages the member 16. 60 65 By further rotation of the bolt in the same

direction, the stop 15 will move away from the nut 12 and the parts will assume the position shown in Fig. 3. As soon as the lug 9 strikes the member 16 a clicking noise will occur which may be heard by the operator, 70 and when this notice occurs the operator may know that the parts have moved from ineffective position to effective position, so, it will be seen that even though the locking members are not visible to the operator, he 75 may accurately determine when they are in effective position, and when they are in ineffective position. On the other hand, when it is desired to release the locking members the bolt 14 will be turned in the opposite direction until the stop 15 engages the nut 12, and by further rotation of the bolt, the locking member 4 will be rotated in the reverse direction until the lug 8 strikes the member 16 and the locking member 4 will then be in 80 85 ineffective position.

In order to prevent undue rattling of the parts of the device, I employ a coil spring 17 which as shown is interposed between the locking member 4 and the plate 3 and surrounds the bolt 14. Not only does this spring serve to prevent rattling but it also insures that the locking member 4 will at all times be in effective engagement with the nut 12 so that the nut 12 will be prevented 90 against rotation around the bolt 14 at all times. Spring 17 also serves to disengage the nose 5 of the locking member from the flange 2 when the bolt 14 is turned in a direction to release the locking member, thus 95 permitting easy working of the parts.

The operation and manner of assembling the parts is thought to be obvious from the foregoing description and drawing, therefore, further description is deemed unnecessary. While I have described my locking device as being used in connection with burial vaults, I desire it to be understood that it is equally well adapted to be used in connection with closures of various other 100 105 types.

It is to be understood that the form of my invention herein shown and described is to be taken as a preferred form of the same and that various minor changes in the 110 shape, size, and arrangement of parts may be resorted to without departing from the spirit of the invention or the scope of the subjoined claims.

I claim:

1. The combination with a casing having an opening therein; of an apertured plate for closing said opening, an apertured locking member rotatably mounted on the inner face of said plate, stops carried by said 115 plate, said stops being disposed in close proximity to the locking member, the latter having a nose to engage a portion of the casing around the opening, and being provided with spaced lugs to engage said stops and 120 125 130

limit the turning of the locking member in either of two positions, a bolt extending through the opening in the plate and aperture in the member, an abutment on the free 5 end of said bolt, and a nut also on the bolt between the abutment and member, said nut and abutment being adapted to bind against each other and cause rotation of the member when the bolt is rotated, said lugs and stops 10 causing such binding of the nut and abutment when the lugs engage the stops.

2. The combination with a casing having an opening therein; of an apertured plate 15 for closing the opening, a plurality of locking members rotatably mounted on the inner face of the plate, each locking member including a nose engageable with a portion of the casing around the opening, a socket in its inner face and a hole opening through 20 the socket and its outer face; a nut non-rotatably seated in said socket, a bolt passing through an aperture in the closing plate, hole in the locking member, and threaded through the nut, and a stop on the 25 free end of the bolt.

3. The combination with a casing having an opening therein; of a plate closing said opening, a plurality of locking members rotatably mounted on the inner face of the 30 plate, each locking member including a nose to engage a portion of the casing around the opening, a flange disposed transversely to said nose, the outer edge of which is curved on a line approximately concentric with the axis of rotation, a hub 35 having a poly-sided socket formed therein adapted to receive a nut, and a bore extending from the bottom of the socket through the outer face of the casting, the aforesaid transverse flange being provided with spaced laterally extending lugs adapted for engagement with stops.

4. As an article of manufacture, a locking member formed from a casting which includes a nose to engage a portion of a casting around an opening, a flange disposed transversely to said nose, the outer edge of which is curved on a line approximately concentric with the axis of rotation, a hub 40 having a poly-sided socket formed therein adapted to receive a nut, and a bore opening through the outer face of the casting, the aforesaid flange being provided with spaced laterally extending lugs, and a plurality of combined stop and guide members 45 carried by the closing plate and disposed in close proximity to the locking members and having portions extending over the outer curved edge of the flange between the lugs, 50 to limit turning movement of the locking members when applied or released.

4. As an article of manufacture, a locking member formed from a casting which includes a nose to engage a portion of a casting around an opening, a flange disposed transversely to said nose, the outer edge of which is curved on a line approximately concentric with the axis of rotation, a hub 55 having a poly-sided socket formed therein adapted to receive a nut, and a bore extending from the bottom of the socket through the outer face of the casting, the aforesaid transverse flange being provided with spaced laterally extending lugs adapted for engagement with stops.

In testimony whereof I have hereunto set my hand.

HENRY H. HARRINGTON.
